UNITED STATES PATENT OFFICE.

FRITZ A. ANDERSON, OF MILTON, WISCONSIN, ASSIGNOR TO BURDICK CABINET COMPANY, A CORPORATION OF WISCONSIN.

WATER-COOLED LAMP.

Application filed May 26, 1921. Serial No. 472,933.

To all whom it may concern:

Be it known that I, FRITZ A. ANDERSON, a citizen of the United States, residing at Milton, in the county of Rock and State of Wisconsin, have invented certain new and useful Improvements in Water-Cooled Lamps, of which the following is a specification.

The invention relates to improvements in water cooled lamps, and more particularly to lamps that are used for therapeutic purposes.

One of the objects of the invention is to improve the construction of such lamps by providing a variable heat conducting medium between the lamp body and the cooled casing of the structure, whereby, with a given cooling means, the extent to which the lamp, *per se*, may be cooled is regulable.

Another object is to provide in the structure a lamp-containing casing within an outer casing, and between which water is made to circulate.

Another object is to provide an elastic means for holding the lamp in the casing, so as to absorb any shocks or vibrations without imparting injury to the lamp.

Another object is to provide improved means for connecting the lamp in circuit.

Another object is to decrease the cost of such structures and to render them more convenient for manipulation and repairs.

Fig. 1 is a vertical section taken substantially on line 1—1 of Fig. 5.

Fig. 2 is a section taken substantially at right angles of Fig. 1.

Fig. 3 is a section taken substantially on line 3—3 of Fig. 2.

Fig. 4 is a section taken substantially on line 4—4 of Fig. 2.

Fig. 5 is a section taken substantially on line 5—5 of Fig. 1.

Fig. 6 is a section taken substantially on line 6—6 of Fig. 2.

Fig. 7 is a ferrule having a variable number of fingers for conducting heat from the lamp to the casing.

In all the views the same reference characters are employed to indicate similar parts.

The outer casing 10 encloses an inner cas-

ing 11 and in the space between the casings water is caused to circulate.

In the outer casing there is a wall 12 which extends transversely across the outer casing, and is provided with a perforation for insertion of the contracted end 11' of the casing 11, as clearly shown in Fig. 1. Below the partition wall 12, and in the outer casing, is another water distributing wall 14, having holes 15 near the front part of the casing, and immediately above the space 16 between the lenses 17 and 18.

Another transverse wall 19 extends across the inside of the outer casing, as shown in Fig. 1 and Fig. 5, and is provided with a larger opening, or hole, for an enlarged part 11^a of the inner casing. A ferrule 20 is insertable in the larger part 11^a of the inner casing and the ring portion 21, of the ferrule, is contained in the contracted part of the opening 11^a, as at 22, the fingers 23 extending downwardly for contact with the surface 24 of the lamp 25. The ferrule 20 may have a greater or less number of fingers 23 for the purpose of carrying away the heat from the surface of the lamp which they contact. By breaking off one or more fingers 23, the heat carrying capacity of the device 20 may be reduced. It is well that the lamp 25 should retain a certain portion of heat in order that it may be efficient and in a lamp of this character it is very desirable that a certain portion of the heat should be carried away by the water circulating between the two casings, so that the light projected from the lamp thru the lenses 17 and 18 may be relatively cool and that the surface of the casing structure may not be maintained at too high a temperature for convenience of handling; therefore the number of fingers 23 that are attached to the ring portion 21 determines the amount of heat that the lower end of the lamp will part with thru the instrumentality of the heat conducting ferrule 20, by the surface of the fingers left depending from the ring portion 21. The fingers 23 also serve as yielding means to prevent any violent lateral vibration that may be imparted to the casing from reaching the lower end of the lamp.

Extending from the partition 12 to the

partition 19, thru the water space, is a tube 26 thru which an electric conducting rod 27 passes to reach the terminal 28 of the lamp structure, where the conductor 27 is connected to a service wire 29 that comes from a suitable source of current supply thru the wire jacket 30.

Located around the opening in the partition plate 12 are a series of spring fingers 31, 10 which are secured to the plate, as at 32, and which have projecting parts 33 extending over the opening in the plate 12 to engage the upper end 34 of the lamp 25. These fingers are yielding and permit some slight 15 vertical movement of the lamp.

Surrounding the lower end 35 of the lamp 25 is a sort of wish bone conductor 36, having its ends 37 and 38 connected together by a flexible wire cable 39 to hold the intermediate parts in intimate contact with the portion 35 of the lamp 25. The point 40 where the ends join is provided with an orifice 41 to receive the conductor 27. A washer 42 is placed over the wire 27 and 25 a spring washer 43 is placed between the conductor 36 and the screw nut 44, so that the lamp 25 is yieldingly supported at its lower end by the conductor 36 and the spring washer, to take up any jar or impact imparted to the structure in a vertical direction. The lamp is therefore spring suspended.

Another conductor 46 is connected to a wire 47 that comes from a suitable source 35 of current supply in the jacket 30 and has an extending elastic end 48 secured to the wire 46 by a nut 50. The end 48 is more or less yielding and is brought into contact with the upper conducting end 51 of the lamp 25 when the lamp is placed in position, so that the electric current for the lamp from the wires 27 and 46 has a completed path thru the conductor 48 and the conductor 27.

45 A ring 54 is secured in the outer wall of the outer casing to hold a block 55 of insulating material for supporting the terminals of the conductors 27 and 46. A handle 64 is provided by an insulating block which 50 is held in place by the water circulating tubes 56 and 57, which are screwed into fittings 55 and 58', respectively, the latter being properly secured to the outer wall of the outer casing.

55 Hollow nuts 60 and 61 are screwed on the outer end of the tubes 56 and 57, respectively, and provide openings in which hose 62 and 63 may be contained, for bringing water to the lamp and in conducting it away from it. The tube 57 is connected to a water conducting pipe 58, which is carried to the partition 19 and is coiled into a ring 69 which is provided with a series of holes 70, so that

the water will pass out thru the holes of the ring 69. The bottom 71 of the lamp structure is secured in place by the screws 72 and it may be provided with holes 73 to permit air to enter the inner casing 11 of the structure.

The arrows show the direction of circulation of the water in the space between the two casings and the space that separates the two lenses, one of which lenses closes the inner casing and the other closes the outer casing.

75 There are air chambers 75 and 76 left in the outer casing between its ends and the respective ends of the two casings.

The lamp 25 extends entirely thru the inner casing and into each of the air chambers in which connections to the electric circuits are made without disturbing the water 80 circulating conduits.

To remove the lamp it is only necessary to unscrew the unit 44 and when the bottom 85 71 is removed the lamp may be moved out of the casing structure.

The part 11° (Fig. 3) of the inner casing is fashioned to provide a light reflector, preferably, more or less parabolic in form. It 90 is located immediately in the rear of the window lenses 17 and 18, and will project the light from the lamp in more or less parallel rays, providing a beam of maximum density and contributing to the efficiency of 95 the device.

Having described my invention what I claim as new and desire to secure by Letters Patent, is:—

1. A water cooled lamp comprising an 100 outer casing; a shorter inner casing spaced apart from the outer casing leaving a water circulating space therebetween and leaving air chambers in the outer casing between the ends of the respective casings; a lamp 105 extending thru the inner casing with its terminals in the respective air chambers to connect the lamp in circuit.

2. A water cooled lamp comprising an outer casing having a light window; a 110 shorter inner casing having a registering light window spaced away from the outer window, said inner casing spaced away from the outer casing leaving a water circulating space therebetween and between the 115 windows and leaving air chambers in the outer casing between the ends of the respective casings; a lamp extending thru the inner casing with its terminals in the respective air chambers, whereby to connect the 120 lamp in circuit.

3. A lamp of the character described comprising an outer casing; an inner casing spaced away from the outer casing to provide a water circulating space and leaving 125 air chambers in the ends of the outer casing

and yielding means in the respective air chambers to support the lamp to protect it from vertical and lateral vibrations.

4. A lamp of the character described 5 comprising an outer casing; an inner casing spaced away from the outer casing to provide a water circulating space and leaving air chambers in the ends of the outer casing; yielding means in the respective air 10 chambers to support the lamp to protect it from vibrations and yielding electrical terminals in said air chambers to connect the lamp in circuit.

5. A lamp of the character described 15 comprising an outer casing; an inner casing spaced away from the outer casing to provide a water circulating space and leaving air chambers in the ends of the outer casing; a handle secured to one side of the 20 outer casing; electric conductors passing thru the handle terminating in the respective air chambers; a lamp extending thru the inner casing and having an electric terminal at each of its ends for cooperation with the 25 respective terminals in said air chambers.

6. A lamp of the character described comprising an outer casing; an inner casing spaced away from the outer casing to provide water circulating spaces and leaving 30 air chambers in the ends of the outer casing; a handle secured to one side of the outer casing; electric conductors passing through the handle terminating in the respective air chambers; a tube extending between 35 the air chambers and thru the water space thru which one of said conductors

pass to the lower air chamber; a lamp extending thru the inner casing and having electric terminals at each of its ends for cooperation with the terminals in said air 40 chambers.

7. A lamp of the character described comprising two spaced apart casings, an inner casing to contain a lamp, an outer casing to support the lamp and inner casing, 45 said casings having spaced apart windows; a transverse wall at each end and an intermediate water distributing wall arranged to cause water to flow between said windows.

8. A lamp of the character described 50 comprising an outer casing; an inner casing spaced away from the outer casing to provide water circulating spaces and leaving air chambers in the ends of the outer casing and means between the lamp and the 55 inner casing to vary the amount of heat carried away from the lamp by the water circulating thru said spaces.

9. A lamp of the character described comprising an outer casing; an inner casing 60 spaced away from the outer casing to provide a water circulating space between the casings; a window lens in each casing between which water circulates, said inner casing formed into a reflector in rear of said 65 windows; a handle secured to one side of the outer casing and conduits passing thru the handle communicating with the chamber between the casings.

In testimony whereof I hereunto subscribed my name.

FRITZ A. ANDERSON.
